SCAFFOLDING

Farris O. Beuchillon, Chattanooga, Tenn.

Application August 30, 1941, Serial No. 409,104

2 Claims. (Cl. 304—40)

My invention relates to scaffolding and more particularly to devices for joining pieces of scaffolding together to form a strong supporting structure with a minimum of elements.

In the prior art of building and painting buildings, houses, walls and the like, it has generally been the practice to construct the scaffolding entirely of wood and to secure the pieces together by means of nails. This required almost as much time and expense as the time or cost of painting a building, erecting a wall or doing whatever other work which necessitated the scaffolding. In taking down such scaffolding a great many of its pieces were injured in the removal or disengagement of the nails and a great deal of additional time was required.

Applicant with a knowledge of all of these defects in and objections to the prior art has for an object of his invention the provision of a scaffolding secured together by a coupling made from a single piece of material.

Applicant has as another object of his invention the provision of a scaffolding made up of upright and cross pieces detachably joined through a coupling device providing support for cross pieces on all sides thereof.

Applicant has as another object of his invention the provision of scaffolding detachably joined through connecting devices which provide a complete support for each cross piece at the point of juncture.

Applicant has as a still further object of his invention the provision of scaffolding which may quickly and easily be assembled and taken down without injury to the various pieces thereof.

Other objects and advantages of my invention will appear from the following specification and accompanying drawing and the novel features thereof will be pointed out in the annexed claims.

In the drawing, Figure 1 is a fragmental perspective of my improved scaffolding. Figure 2 is a longitudinal sectional view through the center of one of my improved couplings or sleeves looking towards one of the rear faces. Figure 3 is a fragmental plan view of a cross member having my improved connecting elements thereon. Figure 4 is a perspective of a modified form of connecting element in position on a cross member.

Referring to the drawing in detail, I designates the body of a connector sleeve or coupling adapted to telescope over the ends of vertical or upright pieces 9, 10 of wood or other material and join them. These vertical pieces may be of any desired cross-section and size but are prefer-

ably 2" x 2" or 4" x 4"; on one set of opposite sides, preferably in the central portion are wings 5, 5 struck inwardly along line 16 leaving windows 6, 6 therein. These wings 5, 5 act as stops or supports for a central partition element 7 which is inserted into one end of the sleeve 1 and welded to the sleeve along its inner faces at 8.

Struck outwardly from the four faces of the sleeve 1 along lines 15, 15 leaving windows 4, 4 are fingers having horizontally extending portions 14, 14 and upstanding or vertical portions 3, 3.

In the faces where the wings 5, 5 are struck inwardly the fingers are above the wings while in the other opposite sides they are below the wings 5, 5. The positioning of these fingers may, however, be reversed, if it is desired, but it is of importance that the fingers in different sets of opposed sides be offset with respect to each other. In this way the cross pieces may extend from the various fingers without interfering with each other.

The sleeve 1 is preferably made of sheet material, being coiled or formed to the proper shape and the free edges welded along the line 2 or otherwise secured together. By making this of sheet material the fingers 3, 14 and wings 5 may be conveniently pressed or punched out.

It will be noted that the fingers are not shown dotted in on the rear faces of the sleeve of Figure 1, but this omission is for clarity, and the full showing of the fingers 3, 14 in both rear faces is made very clearly in Figure 2.

Each cross piece or ledger 12 shown in detail in Figure 3 has a channel shape connector element 11 mounted thereon through screws or nails 13 adjacent each end, and a modified form of the same connector is shown in Figure 4 with flanges 18 turned back at the upper and lower ends or edges for engagement with the faces of member 12 which is preferably of wood, and having screws 19 or other securing means passing therethrough to secure it to the cross members.

As shown in Figure 1 these connectors 11 interlock with fingers 3, 14 and may act as the sole support through a single end of the cross member 12 to support it.

In the form of connector of Figure 3, nails may be employed instead of screws 13 and they may be driven entirely through the cross member 12 and clinched on the back side. This makes a permanent connection which will not likely loosen. On the other hand, the modification of Figure 4 removes the screws 19 to a point where they cannot interfere with the interlocking of the connector 17 and finger 3. Furthermore the

flanges 18 take part of the load and reduce the stress on screws 19.

Having thus described my invention, I claim:

1. A scaffolding structure of the character described comprising upright pieces and cross pieces, a one piece tubular sleeve for telescoping over the ends of adjacent upright pieces, wings struck inwardly from said sleeve intermediate its length, a transverse partition positioned within said sleeve and secured against said wings for engagement with the ends of the upright pieces, fingers struck outwardly from the sides of said sleeve and extending upwardly, and connectors on the cross pieces for interlocking engagement with said fingers to support said cross pieces.

2. A scaffolding structure of the character described comprising upright pieces and cross pieces, a sleeve adapted to telescopically receive the adjoining ends of the upright pieces, fingers struck outwardly from the sides of said sleeve and extending upwardly in off-set relation to said sides forming hangers to receive the ends of said cross pieces, and channel shape connectors carried by the ends of said cross pieces for interlocking engagement with said fingers, said connectors having outwardly projecting flanges overlapping opposite side edges of the fingers to retain the cross pieces against longitudinal movement.
